UNITED STATES PATENT OFFICE

154,568

DESIGN FOR A COMBINATION TUMBLER
AND TOOTHBRUSH HOLDER

Paul F. Simpson, Washington, Conn., assignor to
The Autoyre Company, Incorporated, Oakville,
Conn., a corporation of Connecticut

Application August 28, 1947, Serial No. 141,091

Term of patent 14 years

(Cl. D4—3)

To all whom it may concern:

Be it known that I, Paul F. Simpson, a citizen of the United States, residing at Washington, in the county of Litchfield and State of Connecticut, have invented a new, original, and ornamental Design for a Combination Tumbler and Toothbrush Holder, of which the following is a specification, reference being had to the accompanying drawing, forming a part thereof.

Fig. 1 is a perspective view of the combination tumbler and toothbrush holder showing my new design;

Fig. 2 is a top plan view of Fig. 1;

Fig. 3 is a side elevational view of Fig. 2; and
Fig. 4 is a front elevational view of Fig. 2.

I claim:

The ornamental design for a combination tumbler and toothbrush holder, substantially as shown.

PAUL F. SIMPSON.
